UNITED STATES PATENT OFFICE.

MAE ROBINSON RUDY, OF CHICAGO, ILLINOIS.

FOLDING TABLE.

1,287,444.

Specification of Letters Patent. Patented Dec. 10, 1918.

Application filed August 30, 1916, Serial No. 117,711. Renewed June 5, 1918. Serial No. 238,394.

To all whom it may concern:

Be it known that I, MAE ROBINSON RUDY, a citizen of the United States, residing at Chicago, in the county of Cook and State of Illinois, have invented certain new and useful Improvements in Folding Tables, of which the following is a specification.

This invention relates to folding tables, and is adapted particularly for use with 10 automobiles or like.

The primary object of the invention is to provide a simple and improved table which shall be of light weight, simple construction, which is capable of being folded when not 15 in use to occupy but a small amount of space within or upon the vehicle, which affords a convenient storing place for dishes, knives, forks, cups, thermos bottle, luncheon, and other essential accessories, and which shall 20 afford a maximum in amount of table surface when set up or extended.

A further object of the invention is to provide a device of this character which may be manufactured at comparatively low cost, 25 which shall present a neat and attractive appearance, which shall be constructed in such manner as to occupy but little space but which shall possess sufficient stability or 30 rigidity when set up to adapt itself to its various uses, and which is capable of being readily and quickly extended or folded as required.

The invention has for a still further and particular object to provide a device of this 35 character which is equipped with improved means for locking the legs or supports in proper position when the device is in use.

With these objects in view, together with others which will appear as the description 40 proceeds the invention resides in the novel formation, combination and arrangement of parts, all as will be described more fully hereinafter, illustrated in the drawings, and particularly pointed out in the claims.

45 The invention will be best understood with reference to the accompanying drawings, wherein:

Figure 1 is a perspective view illustrating the improved table in set-up position and 50 ready for use,

Fig. 2 is a similar view showing the table collapsed,

Fig. 3 is a detail perspective view of the under surface of the table when in partly set-up position, and 55

Fig. 4 is a similar view of the luncheon kit adapted to be accommodated by the improved table.

Referring now more particularly to the drawings, the table illustrated is composed 60 of a pair of sections or leaves 5 and 6 the said sections being hinged together as at 7 so as to be capable of folding upon each other to occupy but a small amount of space when not 65 in use. The width and length of the leaves 65 or sections may be varied, it being obvious that the sections may be made on such scale as will permit of the table being set up within a vehicle, or it may be made on a larger scale to be used upon the outside of the 70 carriage. The table may be constructed of wood, light sheet metal or any other suitable material. The extremities of the table sections which are hinged together are shoul- 75 dered as at 8, the said shoulders being adapted to engage and coöperate with each other when in set-up position to maintain a smooth, even and unobstructed top surface for the table. The arrangement also permits of the underfaces of the table sections 80 lying in engagement with each other, whereby the devices may be neatly and compactly folded without presenting any ob- 85 structions. Each of the sections is provided throughout its perimeter with a depending 85 apron or flange and fillers are arranged upon the bottom of the sections adjacent the edges thereof. The fillers are cut away as illus- 90 trated to provide channels 10 adjacent their outermost edges, and hinged as at 11 within the transversely extending channels at the free ends of the table sections are leg frames 95 or supporting members 12. The legs of the supporting members are indicated at 13, and are of a length and width to snugly fit 95 the table sections and to lie within the con- 100 fines of the longitudinally extending channels 10 in the said fillers. The cross bars 14, connecting the free ends of the legs 13, rest within the laterally extending channels at the inner extremities of the table sections. In this manner it is seen that the leg frames may be swung inwardly upon the table sec- 100 tions to lie wholly within the channels ex-

tending around the lower perimeter thereof. When the table is folded these leg frames cannot interfere with the table sections lying close upon each other.

5 Associated with each leg frame for maintaining the same firmly at right angles to their respective upper sections are braces 15. These braces are pivoted at one end to the legs 13 of the frames, and are equipped 10 at their opposite ends with blocks 16 which ride within slots or grooves 17 extending lengthwise of the longitudinal filler members of the table sections. A plate 18 partially closes each slot so as to prevent the 15 block members becoming disengaged therefrom. A locking lever 19 is associated with each of the leg frames for maintaining the same rigidly in proper extended or right angular position. These levers are arranged 20 one upon each of the table sections at the outer or free extremities thereof, and may be mounted for lateral sliding movement within suitable guide openings formed within the outermost transverse filler members. 25 The locking ends of the said levers are adapted to extend into the longitudinally disposed channels or slots 17 in the longitudinally extending filler members whereby, the said levers engage and retain the block 30 members 16 on the braces 15 against inward sliding movement within their slots. The levers at their locking ends are notched as at 20 for engagement with the corners of the longitudinal fillers, whereby accidental 35 displacement of the said levers will be prevented. These levers have their inner extremities turned inwardly as at 21 and extend through suitable apertures in the fillers, whereby the said levers may be conveniently 40 operated when setting or collapsing the table.

The fillers are arranged upon the table section bottoms in such manner as to provide central rectangular compartments 22, 45 the said compartments being adapted when the table is collapsed to house between them a luncheon kit indicated generally at 23. This kit in the present instance is illustrated as comprising a rectangular shallow box, 50 formed of metal or the like and which is provided upon its interior with suitable subdivisions for properly housing dishes, knives and forks, cups and other such articles as may be essential. It will also be observed 55 that ample provision is made for packing food in the receptacles indicated at 30, 31 and 32, the latter being snugly fitted around the dish and utensil compartment. The box is equipped with a lid 24, and the said box 60 is of a depth equal substantially to twice that of the compartments 22. The arrangement is such that when the box 23 is inserted within one of the compartments upon the

table bottom, the opposite table section may be folded upon and snugly engaged over the 65 protruding portion of the box.

The transversely extending filler member at the outer extremity of one of the table sections may be cut away as shown, the cut away portions provide compartments, one 70 for the housing of a thermos bottle 25 or other container and the other compartment 75 26 being adapted to contain such culinary implements as may be required for a meal.

The ends of the table sections may be 75 equipped with handles 27 by means of which the device may be readily carried from place to place.

From this description it is seen I have provided an extremely simple, inexpensive 80 and yet thoroughly convenient collapsible table capable of accomplishing the ends set forth. In adjusting the device to set-up position, the leaves or sections 5 and 6 are swung outwardly until limited against further movement by engagement of the shoulders 8. The leg frames 12 are then rocked to right angular position, whereupon the locking levers 19 are manipulated to prevent folding of the said leg frames. The luncheon kit may be easily removed from the compartments 22.

While the above is a description of the preferred embodiment of the invention, it is obvious that various changes in minor details of construction and arrangement of parts may be resorted to if desired without departing from the spirit of the invention or exceeding the scope of the claims.

What is claimed is:

1. In a device of the class described, a table including a leaf having a laterally disposed channel in its under face, the said under face also being provided with longitudinally disposed channels, one of which communicates with said lateral channel, legs hinged to said leaf and being adapted when folded to fit within said longitudinal channels; a brace connected to one of said legs at one end, a block on the other end of said brace slidably engaged in one of said longitudinal channels, and a locking lever slidably arranged in said laterally disposed channel and being adapted at one end to engage and hold said block against sliding movement, substantially as described.

2. In a device of the class described, a table comprising a pair of leaves hingedly connected together and adapted to fold upon each other, fillers arranged around the edges 120 of said leaves upon the under surfaces thereof, the said fillers being provided with channels, leg frames pivoted to said leaves and adapted to lie within said channels, the said fillers being provided with longitudinally 125 disposed slots, braces pivoted to said legs at

one end and extending at their opposite ends into said slots, blocks on the extremities of said braces, and levers arranged within said fillers at the outer ends of the leaves and
5 adapted to engage said blocks to prevent sliding movement of the same, substantially as described.

In testimony whereof I affix my signature in presence of two witnesses.

MAE ROBINSON RUDY.
